UNITED STATES PATENT OFFICE

2,029,577

MACHINE FOR WINDING ELECTRICAL COILS

Arthur W. Le Boeuf, Cranston, R. I., assignor to
Universal Winding Company, Boston, Mass., a
corporation of Massachusetts

Application April 9, 1932, Serial No. 604,293

17 Claims. (Cl. 242—10)

This invention relates to improvements in winding machines and particularly to machines for winding electrical coils with sheets of paper or other insulating material inserted between the 5 layers of wire or other conductor forming the coil.

In the following specification and claims the term "coil" is used in a broad sense to indicate any form of wound body; the term "wire" to 10 designate all types of conductor; and the term "paper" to apply to sheet insulation generally.

One object of the invention is to provide a machine of the type specified having automatically-operated means for inserting the sheets of paper 15 into the coils at intervals during the winding to provide insulation between the layers of wire.

Another object of the invention is to provide means for supplying the paper or other insulating material from a continuous strip and for measuring and severing the strip in progressively increasing lengths in accordance with the increase 20 in circumference of the coils being wound.

Another object of the invention is to provide means for guiding the paper sheets into place on 25 the coils to insure their proper overlying relationship with respect to the layers of wire.

Another object of the invention is to provide 30 guiding and feeding means for the paper or other insulating material which are adjustable for strips of different widths as used in coils of varying dimensions.

Another object of the invention is to provide 35 a sheet-serving apparatus of the type specified which will operate without wrinkling, buckling, skewing or otherwise mishandling the paper or other insulating material whereby to insure proper delivery of the same to the winding without constant attention on the part of the operator.

Another object of the invention is to provide 40 a sheet-serving apparatus of the type specified which is of simple construction, positive in operation and proof against derangement or getting out of order.

Further objects of the improvement are set 45 forth in the following specification which describes a preferred embodiment of the invention, by way of example, as illustrated by the accompanying drawings. In the drawings:

Fig. 1 is a front elevation of a coil-winding machine showing the general arrangement of the paper-feeding means in connection with the winding mechanism;

Fig. 2 is an enlarged general plan view of the 50 sheet-serving mechanism showing its relation to

the winding mandrel and wire-guides of the machine;

Fig. 3 is an end view of the same showing the delivery-mechanism in operative position during the transfer of the paper sheet to the coils being 5 wound;

Fig. 4 is a side elevation of the sheet-serving means partly in section illustrating the drawing-off, feeding and cutting mechanisms for the paper, and showing the positions of the correlated 10 elements thereof during the delivery of the paper to the winding;

Fig. 5 is a similar part sectional view of the sheet-serving mechanism showing the position of the feed-elevating means at the start of the 15 winding of the coils;

Fig. 6 is a similar part sectional view illustrating the strip-measuring mechanism for controlling the length of the sheet fed into the coils;

Fig. 7 is a part sectional view similar to Fig. 4 20 showing the position of the feed-rolls immediately following the feeding of the paper into the delivery shelf and illustrating the manner in which the feed-rolls are separated to permit the measuring bar to draw an additional length of paper 25 therebetween;

Fig. 8 is a similar part sectional view showing the cutting-off mechanism which operates to sever the strip of paper immediately following the measuring operation;

Fig. 9 is a view similar to Fig. 5 illustrating the manner in which the feed-elevating means acts to raise the sheet of paper into position to be delivered to the windings at a constantly increasing height;

Fig. 10 is a side view of the elevation-control mechanism shown in position to effect delivery of the 35 paper sheet to the coils;

Fig. 11 is an end view of the delivery mechanism shown in position to effect delivery of the 40 paper sheet to the coils;

Fig. 12 is a detailed front view of the sheet-serving means and cutting-off mechanism showing the delivery shelf broken away to illustrate the arrangement of the two cooperating knives 45 for severing the strip of paper;

Fig. 13 is a detailed plan view of the cam-shaft and various cams and levers for actuating the different mechanisms;

Fig. 14 is a detailed sectional view of the sheet- 50 delivery mechanism and elevation-control means taken on line 14—14 of Fig. 3;

Fig. 15 is an enlarged fragmentary end view of the forward part of the sheet-serving means illustrating the manner in which the paper strip 55

is fed by the feed-rolls into the delivery-shelf which is shown in section;

Fig. 16 is a similar enlarged view showing the paper-feed rolls as having separated to permit the strip to be freely drawn therethrough during the measuring operation and also showing the means for gripping and holding the end of the strip in place on the delivery shelf during the measuring of the same;

Fig. 17 is an end view of the adjustable coupling used for timing the sheet-serving mechanism in proper relation with respect to the winding mechanism; and

Fig. 18 is a chart graphically illustrating the path of movement of the various cooperating elements and indicating the sequence of operations of the same during one complete cycle.

For convenience of description the complete machine will be divided into units such as the coil-winding mechanism, sheet-serving apparatus in general, paper supply mechanism, strip-feeding means, strip-measuring means, strip-severing or cutting-off means, delivery-shelf, means for elevating the delivery-shelf and the control therefor, and the sheet-delivery means.

Coil-winding mechanism.—The wire-coiling mechanism herein illustrated is of the same construction as that disclosed in my copending application for United States Letters Patent, Serial No. 560,839, filed September 2, 1931. As the present invention relates more particularly to an improved sheet-serving apparatus for use in connection with such a form of winding mechanism, the wire-coiling mechanism is herein described only briefly as related thereto.

Referring to the drawings, the coil-winding mechanism herein illustrated comprises a bed or table 2 supported by legs 3 adapted to rest on the floor. Fixedly mounted at one end of the bed 2 is a headstock 4 carrying the journals for a rotatable winding-spindle 5. The spindle 5 carries a belt-pulley 7 which may be connected by means of a belt 8 to be driven from any suitable source of power such as an electric motor, not herein shown. At the opposite end of the winding-spindle 5 is a handwheel 9 which is also used as a brake-wheel to effect prompt arrestment of the rotation of the spindle. This end of the spindle 5 carries a socketed chuck 11 for connection with a winding-mandrel or arbor 15 on which one or a plurality of coils C may be wound, the opposite end of the mandrel being received in a similar chuck 12 supported in a tail-stock 13.

The strands of conductor or wire w are fed to the winding-mandrel 15 from above and caused to be traversed longitudinally of the axis thereof by means of reciprocating guides 17. In the present type of machine a plurality of coils or electric windings are produced at one time by providing a series of the wire-guides 17 which are mounted in spaced relationship on a sliding carriage or cross-head 20. The carriage or cross-head 20 is reciprocated from a horizontal traverse-rod 22 which derives its motion from a heart-shaped cam 23 keyed to a shaft 21. The cam 23 is fast with a gear 24 which is driven from the winding-spindle 5 by gearing to be later described. A roll or follower 25 on a stud 30, carried by a block or slide 27, engages a groove 26 in the cam 23 and thereby imparts motion to the slide which is reciprocable on an inclined track-arm 28. A second roll on the forward end of the stud 30 engages in the slot 31 of a vertical arm 32 which is secured fast to the traverse-rod 22. The track-arm 28 is pivoted on the axis 21

of the cam 23 and is angularly adjustable along a fixed quadrant 33. By adjusting the angular position of the track-arm 28 the range of action of the slide 27 is regulated to control the extent of reciprocation of the arm 32 and rod 22 whereby to adjust the length of throw of the wire-guides 17 in accordance with the type of coils to be produced.

The traverse-mechanism of the winding-machine is connected to be driven from the winding-spindle 5 through the means of gearing as next described. The spindle 5 carries a worm 35 which, as described in the copending application previously referred to, is releasably keyed thereto. This construction provides that the worm 35 may be disconnected from driving engagement with the spindle 5, whereby the operation of the wire-traversing and sheet-serving mechanisms may be temporarily arrested while the rotation of the winding-spindle is continued for the purpose explained in the application above referred to. For the purpose of the present description the worm 35 may be considered as normally fast with the spindle 5.

The worm 35 meshes with a worm-wheel 36 which is keyed to a stud-shaft 37 journaled in suitable bearings in a portion of the machine frame. The stud-shaft 37 extends through a gear-casing 38 and on its forward end carries a pinion 40 fast therewith. The pinion 40 meshes with a spur-gear 41 which is fast with a smaller gear 42 and rotatable on a fixed stud 43 secured to an adjustable arm 44. The arm 44 is adjustable about the axis of the stud-shaft 37 to permit the use of change-gears in substitution for the gears 41 and 42. The gear 42 meshes directly with the large gear 24 which drives the cam 23 and thus motion is transmitted from the winding-spindle 5 to the cam to reciprocate the thread-guide in the manner as previously explained.

The manual starting and stopping of the machine is effected through the use of instrumentalities described in the pending application above referred to, and for automatically arresting the winding operation after a predetermined number of layers have been wound into the coils an automatic registering and counting device is provided, but not herein shown. This device forms the subject matter of a separate application, Serial No. 574,391, filed November 11, 1931.

Sheet-serving apparatus in general.—The serving mechanism for inserting sheets of insulating material into the coil or coils being wound is constructed as a complete unit adapted for attachment to the rearward side of the coil-winding machine. As herein illustrated the serving attachment comprises, essentially, a pair of frame-members or brackets 55 and 56, see Figs. 2 and 4, which are attached to the rearward side of the bed 2 by means of bolts 51. The members 55 and 56 furnish supports or bearings for the various shafts of the mechanism to be later described. Extending between the frame-members 55 and 56 at their upper rearward ends is a brace 60 or tie-rod 60. The rod 60 is secured to the members 55 and 56 by means of bolts 61 passed through holes in the members and screwed into threaded holes in the ends of the rod.

The frame-members 55 and 56 are also braced by means of an elongated strut or paper-guide member 62, the latter being secured between the members by means of bolts 63 and dowels 64, see Figs. 3 and 12. The frame-members are further joined together to form a rigid structure by vari-

ous fulcrum-rods which are pinned or otherwise fixedly mounted in bosses on the members. The rearward end of the frame-members 55 and 56 may be supported from the floor by means of a 5 yoke-member 66, see Figs. 4 and 6, which is bolted to the underneath side of the rearward extensions 59 of the members. A threaded rod 67 is attached to the lower end of the yoke 66 and its lower end 10 may carry a suitable foot, not shown, adapted to be screwed to the floor. The complete sheet-serving unit is thus rigidly supported to prevent undue vibration.

As previously stated, the frame-members 55 and 56 constitute bearings for the various shafts 15 and as herein shown bearings or journals 68 and 69 are formed therein for a rotatable cam-shaft 70. The cam-shaft 70 constitutes the main driving element for the several mechanisms and is driven from the winding-spindle 5 through a 20 train of gearing as next described.

It has been explained that the traverse-cam 23 is driven from the spindle 5 by gearing at a reduced rate of speed. Keyed to the traverse-cam shaft 21 is a relatively large spur-gear 72, 25 see Fig. 1, which meshes with a smaller spur-gear 73 rotatably mounted on a stud-shaft 74 held in a bracket 75. The gear 73 is fast with a bevel-gear 76 which meshes with a similar bevel-gear 77 fast on a shaft 78 journaled in a bearing 79 30 formed as a part of the bracket 75. At its opposite end, the shaft 78 carries a coupling member 80 which is joined to a similar member 81 fast on the end of the cam-shaft 70 by means of bolts 82, see Fig. 1. Referring now to Fig. 17, 35 the coupling member 80 is provided with three equally spaced arcuate slots 83 while the member 81 is formed with four similar slots 84. By this means the shafts 78 and 70 may be rotatively adjusted with respect to each other to obtain the 40 proper relationship and then bolted together with the bolts oppositely positioned one hundred and eighty degrees apart.

It is essential that the operation of the sheet-feeding or serving mechanism be properly timed 45 with respect to the traversing of the wire. That is to say, the delivery of each sheet to the coils must take place at the instant that the wire-guides 17 reach their extreme extent of traverse in either direction. To attain this proper timing 50 of the mechanisms the coupling members 80 and 81 are rotatively adjusted relatively of each other and the bolts 82 tightened to clamp them together to rigidly join their shafts 78 and 70 as a unit. The gears 72 and 73 have a ratio of 2 to 1 to provide 55 that the cam-shaft 70 will make one complete revolution during a half revolution of the traverse-cam shaft 21 so that the delivery of the sheet to the coils will take place at the end of each complete traverse of the wire in either direction.

Paper supply mechanism.—Referring to Figs. 2 and 4 of the drawings, a roll R of paper or other insulating material is rotatably mounted on a rod 88 removably supported between the rearward extensions 59 of the frame-members 55 and 56. The roll R is placed on the rod 88 so that its central tube T rests on the tapered sides of one of a pair of frusto-conically shaped collars 89 fixedly mounted on the rod. A similar collar 89 is then 70 slid onto the opposite end of the rod to enter the other end of the tube T. The collars 89 are secured in place by set-screws or other suitable means and thereby the roll R is held rotatively with the rod 88. Adjustable collars 90 secured to 75 the extremities of the rod 88 abutting the outer

sides of the frames 55 and 56 take the thrust in either direction and maintain the paper strip in central position with respect to the feed mechanism.

The end of the paper strip S is drawn off from the roll R and passed around movable rollers 94, 5 to be later described, and thence upwardly and over the tie-rod 60. The strip S is then drawn over a plate-like shelf 91 extending across the top 10 of and fastened to the frame-members 55 and 56. 15 The plate 91 may be constructed from a strip of sheet-metal with end portions 92 bent downwardly at right-angles to its main portion to provide smooth corners so that the paper will not be torn or otherwise damaged during its travel 20 thereacross. From the plate or shelf 91, the paper passes between a pair of feed-rollers 115 and 125 which feed the paper onto a delivery-shelf 225 in the manner as later explained.

The paper strip is drawn off from the roll R 20 during that part of the cycle of operations of the machine as graphically indicated in the chart (Fig. 18), this feeding operation being accomplished by instrumentalities to be next described. Referring to Fig. 4, the rollers 94, before mentioned, are rotatably mounted on a rod 95 secured to the end of a rockable supply-lever 96. The lever 95 is rockably mounted on a pivot-rod 97 extending between the side-frames 55 and 56 and secured in bosses thereof by means of tapered 30 pins 102, see Fig. 13. Spaced at a short distance from its pivot, the lever 96 carries a headed pin 98 on which is rotatably mounted a roll or follower 99 adapted to engage the periphery of an eccentric disk-cam 100 fast on the cam-shaft 70. 35

The supply-lever 96 is held with its roll or follower 99 bearing against the edge of the cam 100 by means of a helical spring 104 surrounding the rod 97, one end of the spring passing through a hole in the lever and the opposite end inserted into a 40 similar hole in a fixed collar 105 on the rod 97, see Figs. 1 and 13. The spring 104 also serves to maintain the hub of the lever 96 in position abutting the side of a collar 106 fast on the rod 97. 45

The supply-control cam 100 and the lever 96 actuated thereby are shown in initial position in Fig. 4, that is, during that part of the cycle of operations as indicated at *a—a* in Fig. 18. With the parts in this relationship the rolls 94 50 are depressed to approximately three-quarters of a complete working stroke. During this stroke the rolls 94 engage the loop of paper strip S and pull downwardly thereon to draw a length from the roll R. When in its lowermost position, as 55 illustrated by dotted lines in Fig. 4, the loop of paper is completely formed. A further rotative movement of the cam 100 permits the follower 99 to ride upwardly whereby the lever 96 and the rolls 94 gradually rise to their uppermost inoperative position as indicated by dash lines in this view. While in this position the loop of paper S is free to be drawn upwardly by the feed-rolls 115 and 125 in the manner as later explained. To provide tension on the suspended length of 60 paper a weight in the form of a cylindrical rod 107 may be placed within the loop to keep the strip taut during its feeding movement.

To prevent the strip S from being drawn rearwardly across the plate 91 and rod 60, a pair of 70 weighted grippers or retainer-elements in the form of eccentrically-mounted disks 111 positioned at the ends of the tie-rod 60 act to check any backward pull upon the strip while it is being drawn off from the roll R as the lever 96 descends. The 75

5 retainers 111 are mounted on arms or brackets 108 adjustably secured to the tie-rod 60 adjacent the edges of the paper strip S. The arms 108 carry pins or studs 110 at their outer ends upon which the disks 111 are eccentrically mounted, and, preferably, the peripheries of the disks are covered with suitable rubber bands to provide frictional resistance to the paper strip passing thereunder. It will be understood by reference 10 to Fig. 4 that the disks 111 offer no resistance to the strip S as it passes over the rod 60 in its travel to the feeding means. On the other hand, as the rolls 94 are lowered to draw off a length of paper from the roll R the disks 111 bear against 15 the marginal edges of the strip to bind it against the rod 60 and prevent retrogressive movement thereof. The arms 108 may be loosened and adjusted along the rod 60 to set the grippers or retainer elements 111 in proper relationship for 20 strips of different widths.

25 *Strip-feeding means.*—In general, the strip-feeding means comprises a pair of opposed rollers 115 and 125 between which the strip passes. The rollers are adapted to be rotated to feed the strip therethrough during a relatively short interval of the cycle of operations as indicated in Fig. 18. Means are provided for swinging one of the rolls away from the other roll after completion of the feeding operation to release the strip so that it 30 may be drawn freely forwardly by a measuring device to be later described.

35 Referring particularly to Figs. 2, 4, 7, 15 and 16, the lower roll 115 is rotatably mounted between the frame-members 55 and 56 in suitable bearings provided for this purpose. The roll 115 comprises an elongated cylindrical body with reduced end portions or trunnions 116 by means of which it is mounted in its bearings adjacent the horizontal strut 62, previously described. The circumference of the roll 115 is provided with annular 40 grooves 117 into which project extensions or fingers 118 of a paper-guide formed as a plate 128 fastened in a recess 118 in the inclined top of the strut or rest 62 by screws 121. The purpose of the 45 guide 128 is to guide the paper strip upwardly across the top of the strut or rest 62 as it leaves the feed-rolls, see Figs. 15 and 16.

50 Spaced slightly above the top of the rest 62 by means of thin plates or shims 142 is an upper guide-plate 153 secured in place by means of screws passing through the plate and its shims and screwed into the rest. The plate 153 is provided with slots 161, see Figs. 2 and 16, and projecting upwardly therethrough is a pair of edge-guide screws 166. The paper strip S passes between the sides of the heads 167 of the screws 166 and is thereby guided laterally across the rest 62.

55 It will be observed by reference to Figs. 15 and 16 that the recess 118 formed in the upper face of the rest 62 is extended laterally with its side beveled upwardly to meet the upper inclined surface of the rest. The screw-heads 167 are similarly beveled to provide that they may be slid therealong while being held from turning. The 60 heads 167 of the screws 166 are clamped against the under side of the plate 153 by means of slotted thumb-nuts 168 which are screwed onto the upwardly extending threaded ends of the screws to secure them in adjusted relationship. 65 Referring to Fig. 2, the sides of the screw-heads 167 act to guide the edges of the strip S as it is fed across the rest 62. By loosening the nuts 168 and sliding the screws 166 in the slots 161 of the plate 153 they may be adjusted to accommodate strips of varying widths.

70 Secured to the end of the lower feed-roll 115 in any suitable manner is a small spur-gear 123 which meshes with a similar gear 126 fast with the upper feed-roll 125. The top roll 125 is rotatably mounted at the ends of a pair of arms 127 and 128 which are fast on a shaft 129 extending through bearings 130 on the frame-members 55 and 56. One arm 127 is formed with an upstanding lug 132, see Fig. 7, through which is threaded an adjustable limiting screw 133. A lifter-lever 162 pivoted on the cross-shaft 129 is formed with a lug 165 adapted to engage the end of the screw 133 to rock the arm 127 to raise the top roll 125 away from the lower roll 115 in the manner and for the purpose as later explained.

75 The end of the shaft 129 extends beyond the bearing 130 on the frame-member 55 and carries a collar 134 fast therewith. A spring 135 is coiled about the shaft 129 between the bearing 130 and collar 134, one of its ends being held within a hole in the side of the collar while its opposite end is bent at right-angles to overlie the top of the frame-member 55, see Figs. 2 and 7. The spring 135 tends to rotate the shaft 129 in a 25 counter-clockwise direction to maintain the top roll 125 in peripheral engagement with the bottom roll 115 until the former is raised by the lifter-lever 162, previously mentioned.

80 As above described, the bottom and top rolls 115 and 125 carry spur-gears 123 and 126, respectively, of the same pitch-diameter which is equal to the diameter of the outer peripheries of the rolls so that when the latter are in contact the teeth of the gears properly intermesh. Furthermore, the movement of the top roll away from the bottom roll is very slight, only a few thousandths of an inch, so that the gear-teeth will not be disengaged. The gears 123 and 126 are intermittently rotated to feed the paper strip by 40 means as next described. The gear 123 on the roll 115 meshes with an idler gear 137 which is journaled on a stud 138 fast in the frame 55 and the latter gear meshes with a larger driving gear 140 journaled on a similar stud 141 in the frame. 45 The gear 140 is periodically rotated throughout a part of a revolution by means of a ratchet-mechanism arranged as now described.

50 A slotted arm 143 pivoted on the stud 141 adjacent the side of the gear 140 carries a pin 144 at 50 its outer end on which is pivoted a pawl 145 adapted to engage with the teeth of the gear 140. A spring 146 maintains the end of the pawl 145 in engagement with the teeth of the gear 140, one end of the spring being hooked to a pin on 55 the pawl and the opposite end looped through a hole in the arm 143. The pawl 145 is moved upwardly to turn the ratchet-gear 140 and thereby the rolls 115 and 125 by means of a connecting rod 154 which derives motion from a feed-cam 60 148 fast on the shaft 70, previously referred to.

65 Pivoted on a fulcrum-rod 149 extending through the frame-members 55 and 56 is a feed-lever 150. The lever 150 carries a pin 151 at its free end upon which is rotatably held a roll or follower 152 engaging the edge of the cam 148, whereby the lever 150 is periodically raised and lowered as the cam rotates in the direction indicated by the arrow in Fig. 7. The hub of the lever 150 abuts the side of the frame 55 and is 70 held thereagainst by a knife-lever to be later described.

75 The lever 150 is connected to impart motion to the arm 143 by means of the connecting rod or link 154. The connecting rod 154 is preferably 75

adjustable in length and for this purpose may be constructed as next described. The main part of the link 154 is adjustably connected to the arm 143 by means of a bolt 155 engaging a slot 158 in the arm. At its lower end the link 154 is threaded to a turnbuckle 157 and the turnbuckle, in turn, is threaded to a bolt 156 connected to the stud 151 at the end of the arm 150. Through this arrangement the length of the connecting rod may be varied to adjust the range of movement of the pawl 145. To provide for the adjustment of the connecting rod on the arm 143 the stud 155 has a square head which is slideable in the slot 158 to be moved toward or away from the axis of the gear 140 and secured in place by a nut. A spring 159 tends to swing the arm 143 downwardly to maintain the roll 152 against the edge of the cam 148, the spring being attached to the pawl pivot-pin 144 and anchored to the machine frame 55 at 160, see Fig. 4.

The lifter-lever 162, previously referred to as pivoted on the rod 129 and operative to raise the top feed-roll 125, is arranged with the lower end of its arm 163 normally bearing against the hub 25 of the pawl-arm 143. A set-screw 164 adjustable in the arm 163 is adapted to be engaged by an angular shoulder 147 on the arm 143 as the latter is raised under the impulse of the feed-cam 148. This engagement rocks the lever 162 to separate the feed-rolls in the manner as previously explained.

Strip-measuring mechanism.—The strip-measuring mechanism comprises a horizontally extending bar or rod 170 which is positioned forwardly of the rest 62 and adapted to be lowered to pull downwardly on the paper strip to form a loop between the delivery-shelf and the rest. The length of this loop is governed by the circumference of the coil or coils being wound at the 40 time the sheet is to be served thereto. As the circumference of the coil constantly increases in length with the growth of the winding, the length of the strip of insulation must increase accordingly. This progressive increase is governed automatically by means as next described.

Referring particularly to Figs. 2 and 6, the measuring rod 170 is supported by legs 171 having laterally extending feet 172 which are attached by screws to the forward ends of a pair of measuring levers 173. The levers 173 have hubs secured fast on a horizontal rod 174 which is rockably mounted in bearings in the frame-members 55 and 56. The lever 173 shown in Fig. 6 has an arcuate tailpiece 175 projecting rearwardly from its hub and carrying a pin 176 at its end. A connecting rod 177 is pivotally connected at its upper end to the pin 176 with its lower end similarly joined to the rearward end of a lever 178. The connecting rod 177 is preferably constructed of three sections screwed together as shown to provide for adjustment in its length.

The lever 178 is pivoted on the shaft 149, previously referred to, being spaced from the side of the frame-member 56 by a washer 179, see Fig. 65 13, and held in place longitudinally of the shaft by a collar 183 fast thereon. At its forward end the lever 178 carries a pin or stud 181 for rotatively supporting a roll or follower 182 adapted 70 to engage the periphery of a disk-like measuring cam 180 fast on the main cam-shaft 70. As will be observed by reference to Fig. 6, the roll 182 is not in constant engagement with the cam 180 being held away therefrom during a part of the 75 cycle of operations through the medium of a

rack-bar or measuring gauge 184. The gauge-bar 184 is slideable in slotted bearings 185 on the frame-member 56, see Figs. 1, 6 and 13, being held in place in the bearings by means of plates 186 fastened thereto. Riveted to the inner side 5 of the gauge-bar 184 is a gauge-finger 187, upon the top of which the follower pivot-pin 181 on the lever 178 normally rests until raised by the cam 180. The pin 181 is maintained in engagement with the finger 187 under the action of a 10 spring 188, the upper end of which is hooked into one of a series of holes in the measuring lever 173 with its lower end anchored to a plate 189 screwed to the frame-member 56.

The measuring operation takes place as the 15 cam 180 frees the follower 182 to allow the pin 181 to descend against the gauge-finger 187, after which time the strip S is severed by means to be later described, see also Fig. 18. As the cam rotates through substantially one-half a complete revolution its edge of greatest radius engages the roll or follower 182 and raises the forward end of the lever 187 to free the pin from the gauge-finger 187. When this action takes place the rearward end of the lever 178 is depressed and through its connection 177 with the lever 173 it raises the forward end of the latter to carry the measuring bar 170 upwardly to the position illustrated by dash lines in Fig. 6 and by full lines in Fig. 15. It will be observed 30 by reference to this latter view that when the bar 170 is in uppermost position, the strip S may pass thereunder in its travel from the rest 162 to the delivery-shelf, indicated generally by the reference character 225.

After the strip S has been fed across the shelf 225, means incorporated therein act to grip the paper to prevent retrogressive movement thereof and at the same time the top feed-roll 125 is raised away from the bottom roll 115 to permit the paper to be drawn freely therethrough. As the cam 180 is further rotated in a clockwise direction, as viewed in Fig. 6, the roll 182 rides down the incline of the cam and its pin 181 is again lowered by the force of the spring 45 188 to the position illustrated by full lines in Fig. 6. In this manner the measuring bar 170 is lowered as illustrated in Fig. 16 to form a loop in the strip of paper.

It has been stated that the length of the loops 50 of paper must be progressively increased during the winding of the coils and to effect this result means are provided for gradually lowering the gauge-finger 187. The gauge-bar 184 is provided with rack-teeth 190 which mesh with the teeth 55 of a pinion gear 191 fast on a rotatable shaft 192. The shaft 192 is rotated by means to be later described. Suffice it to state for the present, that the shaft 192 together with its pinion 191 are intermittently rotated or indexed around through 60 a part of a complete revolution to gradually lower the gauge-finger 187 whereby to cause the measuring bar 170 to be lowered to a progressively increasing extent during the growth of the coils C.

At the start of the winding the circumference of the coils is relatively small and the strip of paper between the rest 62 and the delivery-shelf 225 is of a sufficient length to be wrapped around the coils with a suitable overlap. Consequently, 70 no measuring action of the bar 170 is required and the gauge-finger 187 may be manually adjusted to its uppermost position by means to be later described. After a comparatively few turns of wire have been wound on the winding-mandrel 75

or core, however, the pinion 191 is turned to progressively lower the finger 187 whereby to control the range of movement of the measuring bar 170 in the manner as above explained.

5 *Strip-severing mechanism*—The means for cutting the paper strip to form a sheet of proper dimensions for insertion between the layers of windings comprises a pair of knives, one stationary and the other movable, which cooperate in the manner as later explained.

10 Referring particularly to Figs. 2, 3, 4, 12 and 15, the forward side of the rest 62 is recessed along its length to receive the lower or stationary knife-blade 200 which is fastened thereagainst by screws 201. The upper side of the blade 200
15 is beveled off to provide a shearing edge forming a continuation of the upper inclined surface of the block 62.

The upper or movable knife-blade 205 is pivotally mounted between the forward ends of a pair of arms or levers 203, see Fig. 4, and provided with a lower inclined cutting edge. The arms 203 are fixedly secured to a rod or shaft 204 rotatably supported in hubs or bearings at the top 25 of the frame-members 55 and 56. Referring now to Figs. 2 and 12, the forward ends of the levers 203 are formed with hubs 206 for receiving the reduced cylindrical ends or trunnions 207 of a knife supporting bar 208. The bar 208 is of rectangular cross section and the blade 205 is secured to its flat forward face by means of suitable screws as shown.

The knife 205 moves in an arcuate path and it is therefore essential that its cutting edge be maintained in contact with the sharpened edge of the lower knife 200. For this purpose the left-hand trunnion 207 of the bar is extended beyond its bearing 206 and at its extremity is a fixed collar 210 acted upon by a spring 211. The spring 211 is coiled around the trunnion 207 between the collar 210 and the bearing 206 with its ends secured to each of these elements whereby it tends to rock the bar 208 in the direction to maintain the lower inclined cutting edge of the knife 205 in contact with the cutting edge of the lower knife 200. The arms 203 are maintained in raised position by means as later described and to prevent the knife 205 from swinging back beyond the edge of the knife 200 when in this position a projection 212 formed on the bottom of the upper knife bears against the lower knife. Referring to Figs. 15 and 16, the knife 205 is arranged to slide downwardly between the knife 200 and a paper guide-plate 214 attached to the forward edge of the block 62. The guide-plate 214 supports the paper strip in advance of the fixed knife 200 to provide for the proper cooperation of the edges of the two knives. The paper strip is drawn downwardly from the top of the plate 214 during the measuring operation and the upper edge of the plate is rounded off to provide for a free movement of the paper thereacross.

The arms 203 are operated to carry the knife 205 downwardly to perform the severing operation by means organized as next described. 65 Rockably mounted on the shaft 149 is a knife-operating lever 215 arranged with its hub abutting the hub of the lever 150, previously referred to, and held thereagainst by a collar 216 fixed on the shaft, see Fig. 13. 70 Connected to one arm of the lever 215 by means of a pin 217 is a connecting rod or link 219, the upper end of which is pivotally connected to a pin on one of the knife-levers 203. The link 219 is preferably constructed with end members screw-threaded thereto 75

provide for adjustment in its length whereby to regulate the position of the upper knife 205 with respect to the lower knife 200.

The forward arm of the lever 215 carries a roll or follower 221 which engages the periphery of a knife-cam 220 fast on the cam-shaft 10. Referring to Fig. 4, the cam-roll 221 is here shown in its lowermost position with the rearward end of the lever 215 rocked upwardly and the arms 203 supporting the upper knife 205 elevated. A spring 222 having one end hooked into a hole in the rearward arm of the lever 215 and its opposite end fastened to the upper rod 114 acts to maintain the roll 221 in engagement with the periphery of the cam 220. As the cam 220 rotates through substantially one-hundred and eighty degrees, its eccentric face forces the roll 221 upwardly and the rearward arm of the lever 215 is rocked downwardly against the action of the spring 222. During this movement of the lever 215 the arms 203 are lowered to carry the upper knife 205 downwardly across the fixed knife 200 to sever the paper strip in the manner as later more fully explained. The strip-severing operation takes place immediately following the measuring operation as the inclined cutting edge of the knife 205 makes contact with the cutting edge of the lower knife 200 and cuts the strip S with a shearing action to provide a sheet of predetermined size which is held in and transferred to the coil or coils being wound by the operation of the delivery-shelf 225 to be next described.

Delivery-shelf.—The delivery-shelf 225 is positioned in front of the knives and measuring bar 35 and as herein shown, it comprises a horizontally-extending angle-iron rest or platen 226 supported at its ends by elbow-shaped levers 227 and 228, see Figs. 3 and 12. The levers 227 and 228 have their hubs fixedly secured to a horizontal shaft 40 229 extending between the forward ends of a pair of relatively long arms 230. The hubs of the arms 230 are mounted fast on the ends of a horizontal shaft 231 projecting through bearings on the frame-members 55 and 56. The 45 shaft 231 is adapted to be rotated in its bearings by elevating means, as later described, whereby to elevate the delivery-shelf 225 to the height necessary for effecting delivery of the sheet of paper in proper relation to the periphery of 50 the coil being wound in accordance with the diameter of the latter. During the inoperative stroke of the elevating means the ends of the arms 230 rest upon the top of the bed 2 of the winding machine as shown in Fig. 3. Screwed 55 into bosses at the ends of the arms 230 are bolts 232 arranged with their heads adapted to rest on the top of the bed 2. The bolts 232 may be adjusted to regulate the lowermost position of the arms 230 whereby to govern the initial 60 relation of the delivery-shelf 225 with respect to the coil or coils being wound. The delivery-shelf 225 is normally maintained in close proximity with the measuring bar 170 by resilient means to be later described. To limit the rearward movement of the shelf 225, lugs 234 are provided on the sides of the levers 227 and 228 adapted to engage against finished faces 236 on the frames 55 and 56, see Fig. 15.

As shown in Figs. 12, 15 and 16 the levers 227 and 228 have inwardly projecting ledges 237 to which the angularly-shaped rest or platen 226 is secured. Rising from the top of the ledges 237 are a pair of guide-pins 238 on which a tension-plate 243 is adapted to slide in the man- 75

ner and for the purpose as later explained. The pins 238 have shouldered portions or enlargements 239 which are tapered on the sides to fit into countersunk holes in the platen 226 with their shoulders projecting slightly thereabove, see Fig. 15. The lower threaded ends of the pins 238 extend through holes in the ledges 237 with nuts 241 screwed onto their projecting ends to secure them in place on the levers 227 and 228.

10 Mounted to slide on the upright pins 238 is a tension-plate 243. The plate 243 comprises a sheet-metal strip formed with its rearward side flared upwardly. This flared portion of the plate together with the rearward rounded portion of the angular platen 226 provide a reentrant opening or mouth for receiving the forward edge of the strip of paper as it feeds from the rolls 115 and 125. The tension-plate 243 is mounted to slide on the pins 238 by means of extended bearing sleeves 244.

Riveted to the top of the tension-plate 243 are a pair of fingers 245 which are bent upwardly and rearwardly to adapt their ends to engage with the top of the measuring bar 170 as the latter is raised whereby to lift the plate to permit the paper to be fed thereunder, see Fig. 15. The strip of paper is fed across the platen 226 by the feed-rolls 115 and 125 and the measuring bar then descends to perform the measuring operation by forming a loop in the strip in the manner as previously explained. During the descent of the measuring bar 170 the tension-plate 243 is lowered against the strip on the platen 226. The bottom of the plate 243 is preferably covered with a suitable friction material such as felt which acts to grip the paper strip against the platen. The weight of the plate 243 causes it to "iron out" the wrinkles or ridges in the paper which sometimes occur following the shearing operation. As a further means for flattening the strip and stiffening its projecting end, the plate 243 may be curved downwardly slightly at its forward end as shown at 246.

It is essential that the strip of paper be properly gripped on the delivery-shelf during the measuring operation to prevent retrogressive movement thereof. Referring particularly to Figs. 2, 12, 15 and 16, a pair of sheet-metal fingers 248 attached to the rearward side of the ledges 237 reach upwardly above the plate 243. The upper extremities of the fingers 248 are formed with loops or bearings adapted to receive the ends of a horizontal rod 249 which serves as a pivot for a plurality of gripper-fingers 250. The rod 249 is held against lateral displacement by fixed collars 251 abutting the inner ends of the bearings in the fingers 248. Each tension-finger 250 is constituted by a sheet-metal strip curled around at one end to form a loop encircling the rod 249. The base or main portion of the finger 250 is provided with lateral wings or extensions bent at right-angles to form the sides of a trough in which a resilient detent-member 253, preferably constructed of rubber, is positioned. The lower end of the detent-member 253 projects beyond the end of the finger 250 and is beveled on its under side to provide a frictional surface for gripping and retaining the strip of paper on the gripper-plate 226 in the manner as later explained.

70 The member 253 may be secured to the finger 250 by a screw 254 passing through the rubber with a rectangular washer 255 beneath the head of the screw.

As shown in Figs. 15 and 16, the fingers 250 extend at an angle to the platen 226 and project

through apertures 257 in the tension-plate 243. When the measuring bar 170 is elevated as shown in Fig. 15 the tension-plate 243 is raised and the rearward edges of the apertures 257 engage against the under side of the fingers 250 to swing them upwardly on the pivot-rod 249. The gripper-fingers 253 are thus raised away from the platen 226 to permit the strip S to be slid forwardly thereacross. After the paper strip has been fed onto the platen 226 the measuring bar 170 descends to form a loop. At the start of descent of the bar 170 the tension-plate 243 is lowered to press against the paper and the fingers 250 are immediately released whereby their friction-elements 253 engage the paper. The fingers 253, being angularly positioned, act to grip the paper against the platen 226 to prevent the strip from being drawn rearwardly under the action of the descending measuring bar 170. On the other hand, the forward movement of the paper in feeding to the coils is not resisted by the gripper-fingers.

Elevating means and control therefor.—The sheet of paper or other insulation material, formed in the manner as previously explained, is delivered to the coils for insertion between the layers thereof by a forward swinging movement of the delivery-shelf 225 to the position shown in Fig. 11. The forwardly projecting end of the sheet is delivered to the upper surface of the coil 20 and is drawn thereinto by the wire being wound. In order that the sheet may be fed forward to overlie the top of the coil as it increases in diameter it is necessary that the delivery-shelf 225 be progressively elevated during the progress of the winding. The elevating movement of the shelf must be in proportion to the growth of the coil, its extent being substantially equal to the thickness of a layer of wire plus that of the previously inserted paper sheet. The means for effecting the progressive elevation of the shelf 225 is arranged as next described.

Referring to Figs. 5 and 9, the rod or shaft 231 carrying the arms 230 also has fixed thereon a cam-arm 260. The arm 260 reaches forwardly and is formed on its under side with a cam-face 261 which curves downwardly toward its pivoted end. Adapted to engage with the cam-face 261 of the arm 260 is a lifter-member 263 which is reciprocated in a substantially vertical direction by means of a cam 265 fast on the shaft 70. The lifter-member 263 has a lower forked end straddling the sides of the cam-shaft 70 and carrying a follower or roll 264 which makes contact with the peripheral edge of the cam 265 to periodically raise and lower the lifter. The lifter-member 263 is positioned against the side of the cam 265 and held from displacement in the opposite direction by a collar 266 fast on the shaft 70.

The upper end of the lifter-member 263 is adapted to engage against the cam-face 261 of the elevation-arm 260 to raise it upwardly whereby to rock its shaft 231 and raise the arms 230. In this manner the levers 227 and 228 carrying the delivery-shelf 225 are bodily raised to the position necessary to effect delivery of the sheet to the coils, see Fig. 9.

The forward edge of the lifter-member 263 engages against the edge of an elevation-control cam 270 fast on the shaft 192, previously described as carrying the pinion-gear 191, see Fig. 6. The member 263 is maintained yieldingly bearing against the cam 270 by a coil-spring 268. The spring 268 has one end fastened to an angular finger 269 screwed to the lifter-member and its

opposite end is attached to an arm 271 fast on the tie-rod 97.

At the start of the winding operation the coils C are relatively small in diameter and the elevation of the delivery-shelf is unnecessary to effect proper transfer of the sheet to the coils. Therefore, the cam 270 is provided with a straight edge-portion 273 along which the lifter 263 slides. When the control cam 270 is in the position shown in Fig. 5 the lifter 263 will be reciprocated vertically by the rotating cam 265 with its upper end moving from the position shown by dash lines to that illustrated by full lines. Under this action the lifter-member 263 does not engage the cam-face 261 of the arm 260 and consequently no elevation of the delivery-shelf 225 takes place.

Immediately the coils start to build up, however, the control cam 270 is slowly rotated in a clockwise direction, as viewed in Fig. 5, whereby its eccentric edge-portion gradually swings the lifter-member 263 rearwardly against the action of the spring 268. Now, as the lifter-member 263 continues to be reciprocated by the cam 265 its upper end engages the cam-face 261 on the member 260 to raise the latter and thereby the delivery-shelf 225. During a complete cycle of operations the control cam 270 is intermittently rotated to a slight extent and at each turning movement thereof it moves the lifter 263 longitudinally of the inclined cam-face 261 on the arm 260. The lifter 263 is therefore caused to engage the cam-face 261 successively at points advancing progressively toward the rearward lower end thereof.

55 The shaft 192 to which the control cam 270 is secured is rotated by means to be next described. Referring particularly to Figs. 3, 10 and 14, the shaft 192 projects beyond the frame-member 56 and carries adjacent its bearing in the frame a spur-gear 276 pinned thereto. The gear 276 meshes with a pinion-gear 277 keyed to the hub of a ratchet-wheel 279. The pinion and ratchet-wheel are rotatably mounted on a stud-shaft 280 secured to the frame member 56. As herein shown 40 the stud-shaft 280 has an enlarged head 281 at its end and surrounding the stud between its head 281 and the hub of the ratchet-wheel 279 is a coil-spring 283 which frictionally resists retrogressive movement of the wheel.

50 The ratchet-wheel 279 is intermittently rotated to a slight extent by means of a pawl 285 pivotally mounted on a pin 286 carried at the forward end of a lever 287. The free end of the pawl 285 is maintained in engagement with the teeth of the ratchet-wheel by the force of a spring 289, the ends of which are hooked to pins 290 and 291 on the pawl 285 and lever 287, respectively. The tension of the spring 289 is very slight to permit the pawl to be manually disengaged from the ratchet-teeth in the manner and for the purpose as later explained.

65 The lever 287 is rocked upwardly to cause the pawl 285 to advance the ratchet-wheel 279 by means of an adjustable cam 293, see Figs. 3 and 14, engaging a roll or follower 295 carried on a pin 294 on the lever. As herein shown the cam 293 is made of three separate elements; namely, an annulus 298, a hub 299 and a slidably adjustable cam-block 300 held therebetween. The annulus 298 surrounds the end of the cam-shaft 70 abutting the side of a bearing on the frame 56 and is provided with a diametrically-extending slot 296 in its face. The slot 296 extends only part way across the face of the annulus so 70 that provision is made for a radial set-screw

297 at one end thereof. The cam-block 300 is adapted to be slid radially in the slot 296 of the annulus 298 whereby to project its pointed end 301 beyond the periphery of the annulus 298, see Fig. 10. The block 300 has a slot 302 through which the shaft 70 extends to provide for this adjustment. Referring now to Fig. 14, it will be observed that the slide-block 300 is slightly greater in thickness than the depth of the groove 296 so that as the annulus 298 and hub 299 are drawn together by means of bolts 303 the block 300 will be securely clamped therebetween in its adjusted position.

5 The roll or follower 295 on the lever 287 rides on the periphery of the annulus 298 during the greater part of the cycle of operations whereby the elevation-control mechanism for the delivery-shelf 225 remains inoperative. During that part of the cycle in which the delivery-shelf 225 is being returned to position to receive the feeding paper strip, however, the pointed end 301 of the cam-block 300 moves into position to engage the roll or follower 295 to lift the lever 287. During this upward movement of the lever 287 the pawl 285 acts to advance the ratchet-wheel 279 to an extent which is regulated by the position of adjustment of the cam-block 300. The ratchet-wheel 279 turns the gear 277 to drive the gear 276 and thereby the shaft 192 is rotated to turn the control cam 270 through a part of a complete revolution for the purpose as before explained. Through the intermittent turning of the shaft 192 the pinion-gear 190 is rotated to lower the rack-bar 184 and its attached gauge-finger 187 whereby a progressive increase in the descent of the measuring bar 170 is effected as previously explained.

40 For winding coils from wire of different size or gauge and using insulation of different thickness the rotative movement of the control cam 270 and the downward travel of the gauge-finger 187 must be varied accordingly. For this purpose the cam-block 300 is adjustable in the annulus 298 to regulate the extent to which its pointed end 301 projects beyond the periphery of the annulus. By adjusting the throw of the cam 300 the extent of movement of the arm 287 and pawl 285 is regulated. This adjustment is accomplished by first loosening the bolts 303 to permit sliding movement of the block 300 in the slot 296. 45 The set-screw 297 is then turned to engage the inner end of the block whereby a precise radial adjustment of the block is effected, the block being pushed outwardly or inwardly according to requirements as determined by the size of the wire and the thickness of the paper. After this adjustment is made the bolts 303 are again tightened to clamp the cam-block 300 in place.

50 The cam-shaft 192 is periodically rotated throughout the coil-winding operation by the instrumentalities described above and manually-operable means are provided for resetting the shaft 192 to initial position after the completion of the coil winding. When the machine is first started to perform the winding operation the control cam 270 must be turned to the position illustrated in Fig. 5 with its flat surface 273 in contact with the lifter-member 263. At the same time the gauge-finger 187, see Fig. 6, must be raised to render the measuring bar 170 inoperative. This resetting of the parts is effected manually by means as next described.

55 Referring particularly to Figs. 10 and 14, the shaft 192 extends outwardly beyond the hub of the gear 276 and upon its end is an arm 306 70

secured thereto by means of a bolt 309 passing through its split hub. The arm 306 carries a pin or stud 307, the inner end of which passes through an enlarged circular hole 308 in the side of a crank-handle 310. The crank 310 has a hub 311 loosely mounted on the shaft 192 between the arm 306 and the hub of the gear 276. The hub of the crank 310 is provided with a circumferential groove 312 engaged by the upper hooked end 314 of a pawl-release rod 315. The hook 314 of the rod 315 frictionally engages the groove 312 to resist the turning movement of the rod 315 on the hub of the crank 310.

The lower end of the rod 315 is positioned between the pin 291 projecting from the top of the pawl 285 and the pivot 286 of the pawl and during the winding operation rests against the latter as shown in Fig. 10. A spring 316 coiled about the hub of the crank 310 tends to rotate the latter to hold the rod in the position as above described. One end of the spring 316 is anchored to a screw 318 on the hub of the crank while its opposite end passes through a hole in the projecting end of the pin 307 as shown in Fig. 14. The turning movement of the crank 310 is limited by the pin 307 engaging the side of the enlarged hole 308 therein.

After the completion of one or a series of coils the machine is adjusted for another winding operation by turning the crank 310 in a counter-clockwise direction until it strikes the rearward edge of the bed 2, see Fig. 3. At the first movement of the crank in this direction its hub is rotated on the shaft 192 against the tension of the spring 316 until the side of its hole 308 contacts with the pin 307. During this initial movement of the crank the rod 315 is rocked to cause its lower end to contact with the pin 291 on the pawl 285 whereby to disengage the latter from the teeth of the ratchet-wheel 279. Under this movement the rod 315 eventually brings up against the end of the follower-pin 294 which serves as a stop therefor.

After the pawl 285 has been released from the ratchet 279 continued movement of the crank 310 turns the arm 306, through the medium of the pin 307, to thereby rotate the shaft 192. The turning of the shaft 192 causes the gears 276 and 277 to return the ratchet-wheel 279 to first or starting position. As the crank 310 strikes the bed 2 it is released by the operator and the spring 316 then acts to turn it back slightly as limited by the engagement of the pin 307 with the opposite side of the hole 308, at which juncture the lower end of the rod 315 releases the pawl 285 to allow it to again engage the teeth of the ratchet-wheel 279.

Delivery mechanism.—The delivery or transfer of the sheet of paper or other insulating material to the coils is effected by rocking the delivery-levers 227 and 228 to carry the shelf 225 forwardly to the position as shown in Fig. 11. The sheet of insulation is delivered above the coils and drawn thereinto by the wires *w* as they are wound thereon. The means for tilting or rocking the levers 227 and 228 are arranged as next described.

As shown in Figs. 3 and 11, the lever 228 is constructed with a slotted arm 325 projecting rearwardly from its hub. A stud 326 secured in the slot of the arm 325 provides means for adjustably attaching a vertical bar 328 thereto. The bar 328 extends downwardly to a point below the axis of the cam-shaft 70 and attached to its lower end is a spring 329. The opposite end

of the spring 329 is anchored to a bracket 330 clamped to the leg 3 of the winding machine. The spring 329 urges the bar 328 downwardly to swing the levers 227 and 228 rearwardly until their lugs 234 bring up against the forward faces 5 236 of the frame members 55 and 56. When the levers 227 and 228 are in this position the delivery-shelf 225 extending between their upper ends is positioned to receive the end of the strip S as it feeds forward in the manner as before 10 explained.

The bar 328 is raised to swing the levers 227 and 228 forwardly to perform the delivery or transfer operation under the impulse of a delivery-cam 335 fixedly mounted on the end of 15 the cam-shaft 70, see Figs. 11 and 14. A lever 332 pivoted on the fulcrum-rod 149 and held in place against the arm 287 by a collar 342, see Fig. 13, extends forwardly from the rod. Intermediate the ends of the lever 332 is a pin or stud 20 333 on which is rotatably mounted a roll or follower 334 which engages the edge of the cam 335. The cam 335 is formed with the greater portion of its periphery concentric with its axis but interrupted by a radially projecting point 345 on 25 which the roll 334 rides to rapidly raise and lower the arm 332.

At its extreme forward end the lever 332 carries a pin 336, see Fig. 13, on which is pivotally mounted a dogging arm 337. The dog 337 is 30 formed on one side with an angular slot 338, the sides of which straddle the bar 328, the latter being slidably held in the slot by a sheet-metal plate 339 secured to the side of the dog. The slot 338 in the dog 337 is slightly wider than the 35 bar 328 whereby the latter is permitted to slide freely therein as the levers 227 and 228 are raised with the arms 230. The free end of the dog 337 normally rests on the upper end of an adjustable stop-screw 340 screwed into a stud 341 projecting from the frame-member 56. The stop-screw 340 acts to limit the downward movement of the end of the dog 337 whereby the inclined slot 338 in the latter number is maintained in parallel relation with respect to the sides of the bar 328 45 when the lever 332 is lowered by the cam 335. By this provision the bar 328 may be raised or lowered with respect to the dog under the action of the shelf-elevating mechanism.

The shelf 225 is maintained in elevated position during the delivery of the paper sheet and is lowered after the delivery-mechanism has come to rest. For periodically connecting these two mechanisms the floating dog 337 effects a temporary connection therebetween. In operation, 55 the bar 328 is slid upwardly through the slot 338 of the dog 337 under the action of the elevating mechanism previously described. After the shelf 225 has been raised to the required height the projection 345 on the cam 335 rides under the 60 roll 334 to raise the arm 332 and with it the dog 337. During this movement of the arm 332 the dog 337 rocks downwardly on its pivot 336 under the action of gravity and by its canting action grips the bar 328 to raise the latter to rock the 65 arms 227 and 228 whereby to swing the delivery-shelf 225 toward the coils C to effect delivery of the sheet insulation. Preferably, the bar 328 is serrated or knurled on its side to insure a positive grip of the dog 337 therewith. 70

As the cam 335 continues to rotate the roll 334 rides down the incline of the projection 345 and the dog 337 is lowered until its end contacts with the stop-screw 340, whereupon the dog 337 is canted upwardly to bring the sides of its slot 338 75

in parallel relation to the sides of the bar 328. The dog 337 is thus released from engagement with the bar and the latter is drawn downwardly under the force of the spring 329 until the lugs 5 234 on the levers 227 and 228 bring up against the forward face of the frame-members 55 and 56. Immediately following this movement the elevating mechanism lowers the shelf 225 into position to receive a fresh length of paper strip.

10 *Method of operation of the complete machine.*—As the functioning of the various mechanisms of the machine has already been briefly explained in connection with the description of their cooperating elements, the method of operation of the complete apparatus will now be explained only as relating to the sequence of operations necessary to supply insulation to the coils. Reference is made to the diagram or chart shown in Fig. 18 which indicates the position of 15 the various elements and their relationship during one complete cycle of operations.

In the chart or diagram the dot-and-dash line 20 *a—a* indicates a point in the cycle of operations of the various correlated mechanisms when their 25 elements are in the position shown in the Figs. 1 to 6, inclusive. The reference character *x* on the chart indicates in each instance the point in the cycle reached by the particular mechanism designated when the parts thereof are in the position 30 illustrated in Figs. 7 to 10, inclusive.

Referring first to Fig. 1 of the drawings, the coil-winding mechanism is prepared for operation by placing a suitable paper or fiber tube *t* on the arbor 15 and applying the ends of the latter to 35 the chucks 11 and 12 in the manner as explained in the copending application previously mentioned.

A supply of wire or other conductor is provided by mounting spools, not herein shown, in convenient position above the winding-arbor. The 40 strands of wire *w* are drawn off from the spools under the control of devices for regulating their rotation to apply the proper tension to the wire, and the ends of the strands are attached to the 45 tube *t* on the arbor 15 in proper position to start the winding.

A roll of strip insulating material, such as paper, is supplied for delivery to the sheet-feeding means, see Fig. 4, with the forward edge of 50 the strip drawn off from the roll *R*, passed around the supply-rollers 94 and over the tie-rod 60. The strip *S* is placed on top of the plate 91 and entered between the feed-rolls 115 and 125; the upper roll 125 being lifted manually for 55 this purpose.

With the machine thus prepared for simultaneously winding a series of electrical coils, the operator starts its operation by rocking a starting lever, not herein shown, to close an electric 60 switch, thereby supplying current to the driving motor. The motor is arranged to drive the spindle 5 through the medium of the belt 8 and the traverse-motion is operated therefrom through the geared connection described. By 65 the use of suitable change-gears 41 and 42 the ratio of speed between the traverse-bar 22 and spindle 5 may be controlled to lay the turns or convolutions of wire in proper relationship on the tube *t* to produce the coils indicated at *C*. The 70 extent of traverse of the wire-guides 17 is regulated in accordance with the length of coil required by angularly adjusting the track-arm 28 along the fixed quadrant 33.

The wire-traversing and paper-feeding mechanisms are driven in unison by means of the gears 75

12, 13, 16 and 17 and, as before stated, it is necessary that the delivery of each sheet of insulation to the coils take place as the wire-guides reach their extremes of traverse in either direction. For this purpose the cam-shaft 70 is adjusted 5 in proper relationship with the shaft 78 driven from the traverse-mechanism by means of the adjustable coupling 80, 81 in the manner as before explained.

Assuming that the wire *w* has been traversed 10 along the tube *t* by the guides 17 and the latter have very nearly reached the end of their reciprocating movement, the various mechanisms embodied in the paper-serving apparatus will assume the positions as illustrated in Figs. 3, 4, 15 20 5 and 6, this point in the cycle of operations being indicated at *a—a* in the chart (Fig. 18). At this point the delivery of a measured sheet of paper to the coils *C* is taking place, being approximately one-half completed, while the paper strip is being drawn from the roll *R* by the rollers 25 94 actuated by the supply-cam 100. The feed-rolls 115 and 125 are inoperative with the paper strip gripped therebetween and the measuring bar 170 is being raised from its lowermost position under the impulse of the measuring cam 180. The upper knife 205 has severed the paper strip to form a sheet and is now in raised or inoperative position while the fingers 250 are depressed to grip the sheet to the shelf 225. The 30 elevation-control mechanism has not yet indexed the control-cam 270 around to a sufficient extent to effect the lifting of the delivery-shelf 225 under the impulse of the elevation-cam 265, see especially Fig. 5 of the drawings.

As above stated, the delivery-mechanism is operative at this point and the severed sheet of paper is being transferred to the coils *C*. Meanwhile, the delivery-bar 328, see Fig. 11, is being raised by the dog 337 which is temporarily connected therewith and actuated by the arm 332 moved from the delivery-cam 335 in the manner as before explained. As the winding operation progresses and the wire-guides 17 reach the end of their traverse the delivery-shelf 225 assumes a 40 45 position in close proximity to the coils *C* whereby the forward edge of the paper sheet will be deposited upon the upper surface of the coils in under the wire *w* leading thereto from the guides 17 as shown in Fig. 11. The edge of the sheet is 50 thus caused to be gripped and held by the wire as the traverse of the guides 17 is reversed. Thereafter the rotation of the coils with the mandrel 15 draws the sheet off from the delivery-shelf 225 and as it feeds into the coils it supplies 55 an insulating medium between the completed layer of wire and the next succeeding one deposited thereon. The delivery of the sheet takes place during that part of a complete cycle of operations indicated at *b—b* in the chart, Fig. 18, 60 65 the relationship of the various mechanisms being as above explained.

Assuming now that the first sheet of insulation has been transferred to the coils and a new cycle of operations is about to start, the drawing off of 65 the paper from the roll *R* will be considered as the first operation in the cycle. To effect this the rollers 94, see Figs. 4 and 13, are moved downwardly under the action of the cam 100 to draw off an ample supply of the strip *S* from the roll. During the descent of the rollers 94 the rubber-covered eccentrically-mounted disks 111 act with a wedging effect to bind the strip against the rod 60 to prevent it from being drawn back from the plate 91.

After a sufficient length of paper has been drawn off from the roll R, the rollers 94 ascend to the position illustrated by the dash lines in Fig. 4. During this return movement the feed-cam 148, see Fig. 7, is rotated to raise the link 154 to swing the arm 143 upwardly whereby the pawl 145 acts to rotate the gear 140 throughout a part of a complete revolution, the extent of this motion being adjusted by the regulating means previously described. Through the gear-train 140, 137, 123 and 126, the rolls 115 and 125 are rotated in opposite directions to feed the paper strip S therebetween. It will be seen by reference to Figs. 7 and 15 that as the paper strip S is fed forwardly by the feed-rolls the measuring bar 170 is in raised position and the tension-plate 243 is elevated whereby to permit the paper strip to pass thereunder. As the pawl-arm 143 reaches its upper extent of movement its abutment or shoulder 147 strikes the adjustable contact-screw 164 on the lifter-member 162, thereby turning the latter on its axis 129. The lug 165 on the member 162 is thereby caused to contact with the adjusting screw 133 in the lug 132 on the arm 127 carrying the top roll 125 whereby the roll is raised away from the lower roll 115 to permit the strip S to be drawn therebetween by the measuring bar 170.

Immediately the upper feed-roll 125 is raised the measuring operation takes place as indicated in the chart, Fig. 18. Referring now to Fig. 6, the measuring bar 170 is held in raised position by means of the cam 180. As the cam 180 rotates the roll or follower 182 rides down its inclined face until the pin 181 strikes the gauge-finger 187 on the gauge-bar 184. Coincident with the downward movement of the follower 182 the horizontal bar 170 is lowered. The tension-plate 243 is thus released, see Fig. 16, to allow it to drop under the influence of gravity whereby its associated tension-fingers 250 act to grip the paper strip against the rest 226 to prevent retrogressive movement thereof. As before explained, the measuring bar 170 has no downward movement at the first traverse of the wire because the gauge-finger 187 is in uppermost position to prevent such movement. However, during successive traverses the gauge-finger 187 is periodically lowered at a uniform rate to allow the measuring bar 170 to descend to a constantly increasing extent.

As the measuring-bar descends it engages the strip of paper and draws it downwardly to form a loop therein, the length of the loop being governed by the growth in the coils being wound. When winding wire of large diameter the circumference or perimeter increases rapidly while coils wound with fine wire increase in size very slowly. For this reason the throw of the control-cam 293 is adjusted in the manner as before explained so that the indexing of the shaft 191, and thereby the rate of displacement of the gauge-finger 187, under the action of the pawl 285, may be regulated as required.

After the measuring operation is completed the feed-roll actuating mechanism, shown in Fig. 7, returns to inoperative position and the top-roll 125 is again lowered upon the lower-roll 115. During this latter movement the upper knife 205 descends to cut the strip of paper S to form a severed sheet which is held on the delivery-shelf 225 for transfer to the coils. The knife 205 is moved downwardly under the action of the cam 220, see Fig. 8, which, through the link connection 219 rocks the arms 203. The lower

sharpened edge of the knife 205 is held against the cutting edge of the stationary knife 200 by means previously described to cause it to act with a shearing effect to sever the strip S resting across the knife 200.

As the cutting operation is completed the elevating mechanism acts to raise the delivery-shelf 225 into position to transfer the sheet to the coils C. Referring to Figs. 5 and 9, the elevation of the shelf 225 is effected by means of the lifter-member 263 which is raised by the cam 265. As before explained the lifter-member 263 makes contact with the cam-face 261 on the arm 260 to raise the latter and thereby rock the longer arms 230 carrying the delivery-shelf 225.

When winding the first few layers of coils if relatively fine wire is being used it is not necessary to elevate the shelf 225 since the position of the sheet of paper is initially adjusted in proper relation to the top of the coils by means of the adjusting screws 232 carried on the forward end of the arms 230 and resting against the top of the bed 2. After the first few layers have been wound into the coils, however, the shelf 225 must be periodically raised to insure that the sheet will properly overlie the top of the coils for the purpose as before explained. The lifter-member 263 is therefore not caused to contact with the cam-face 261 of the arm 260 during the first windings, but as the coils increase in size the lifter is eventually moved into position to strike the arm. As previously explained, this positioning of the lifter-member 263 is accomplished by gradually rocking it on its pivot under the action of the control-cam 270. The cam 270 is fast on the shaft 192 carrying the pinion-gear 191 for operating the measuring-gauge finger 187, see Fig. 6. As the finger 187 is progressively lowered to compensate for the increase in size of the coils C, so is the cam 270 slowly rotated to rock the lifter 263 to the right, as viewed in Fig. 9, whereby to effect a gradual rise of the delivery-shelf 225. The extent of shifting movement of the lifter-member 263 depends upon the size of the wire and the thickness of the paper being used, being variable by adjustment of the index-cam 293, for the ratchet-mechanism shown in Fig. 10. This adjustment also regulates the change in position of the gauge-finger 187.

Immediately the delivery-shelf 225 has been elevated it is rocked forwardly to transfer the paper sheet to the coils C. As indicated on the chart, Fig. 18, the pay-off rolls 94 are lowered to draw off another supply of paper from the roll R during the transfer of the severed sheet to the coils; and meanwhile the knife 205 moves upwardly and the measuring bar 170 is also raised. As before explained, the transfer or sheet-delivery is effected by means of the cam-actuated dog 337, shown in Fig. 11, which engages the delivery-bar 328. At this point in the cycle of operations the delivery-cam 335 turns to the position illustrated in Fig. 11 and the dog 337 having gripped the bar 328 lifts the latter to rock the lever 227. The delivery-shelf 225 is thus swung into position above the coils C so that the projecting end of the paper sheet carried thereby is gripped beneath the wires w winding thereon at the instant that the traverse of the wire is reversed. As the wires bind the sheet to the coils the tension-fingers 250 swing upwardly on their pivot 248 to release the paper to permit it to feed into the coils.

It has been explained that the delivery operation is very rapid so that the shelf 225 may be immediately returned to position to receive a

fresh length of paper to be severed from the strip S. As the shelf 225 is returned to initial position the paper-supply mechanism completes the operation of drawing off a fresh supply of paper from the roll R while the measuring-bar 170 is raised to allow the strip to be fed thereunder. The tension-fingers 250 are raised simultaneously with the measuring-bar 170 to permit the strip to be fed onto the shelf-plate 226. At this point the pawl 285 is actuated by the cam 293, see Fig. 10, to index the elevation-control cam 270 and position the gauge-finger 187 whereby to reset the various mechanisms in position to start a new cycle of operations in the manner as above explained.

The various operations above explained are repeated during the winding of the coils until a predetermined number of turns of wire have been wound thereinto. Automatically actuated means, not herein shown, then act to arrest the operation of the machine. Upon the arrestment of the winding operation the operator separates the coils by cutting through the sheets of insulating material in the manner as explained in the application hereinbefore referred to, the coils being then removed from the machine with the mandrel 15 and a fresh winding mandrel placed in the chucks 11 and 12. After the wires w have been attached to the mandrel 15 the paper-serving apparatus is reset by drawing the crank-handle 310 forwardly to the position shown in Fig. 3. The crank-handle 310 is thus caused to actuate the instrumentalities before described to reset the measuring-bar 170 and the lifter-member 263 in first position for winding another set of coils.

It will be observed from the foregoing that the present invention provides means for applying sheets of paper or other insulating material to the coils at the completion of each layer of winding. The machine is entirely automatic in its operation and when once adjusted in accordance with the requirements of the winding it operates continuously without further attention on the part of the operator. The sheet serving means operates with accuracy and precision to properly insert the sheets of insulating material into the coils without crinkling or skewing whereby to produce perfectly formed coils.

While I have herein described and illustrated the present machine as embodied in a preferred form of construction, it is to be understood that various modifications may be made therein without departing from the spirit or scope of the invention. Therefore, without limiting myself in this respect, I claim:

1. In a machine for producing electrical coils, the combination of means for winding a conductor, means for feeding a strip of insulating material, a measuring bar movable across the path of the strip to draw out a loop of predetermined length, a lever for operating the measuring bar, a cam for moving the lever in one direction, a stop for limiting the movement of the lever in the opposite direction, and ratchet-operated means for progressively displacing the stop to regulate the range of action of the measuring bar.

2. In a coil-winding machine, the combination of means for winding a conductor, means for feeding a strip of insulating material, means for drawing out a loop in the strip to measure a predetermined length thereof, a lever for operating said last-named means, a cam for actuating the lever, a rack-bar, a stop on said rack-bar adapted to engage the lever to limit the range of move-

ment of the latter, a pinion for sliding the rack-bar to alter the position of the stop, and means for periodically rotating the pinion.

3. In a machine for winding electrical coils, the combination of means for winding a conductor, means for feeding a strip of insulating material, a measuring bar movable across the path of the strip to form a loop therein of predetermined length, a spring for moving the measuring bar in one direction, a lever for moving the measuring bar in the opposite direction, a cam for actuating the lever, a stop for limiting the action of the lever under the force of the spring to define the range of movement of the measuring bar, and means for periodically displacing the stop to progressively alter the range of movement of the measuring bar.

4. In a coil-winding machine, the combination of means for winding a conductor, and means for feeding a strip of insulating material comprising: a pair of rolls, means for mounting one of the rolls to adapt it to move away from the opposite roll, a ratchet-wheel for periodically rotating the rolls, a rockable arm, means for rocking the arm, a pawl carried by the arm to rotate the ratchet-wheel, and means actuated by the arm at the end of its rocking motion to carry the movable roll away from the opposite roll.

5. In a machine for winding electrical coils, the combination of means for winding a conductor, and means for feeding a strip of insulating material comprising: a pair of opposite rolls, a hinger arm on which one of said rolls is journaled to adapt it to move away from the opposite roll, gearing for rotating the rolls, a ratchet-wheel for driving the gearing, a rockable arm, means for rocking said arm, a pawl on said arm engageable with the teeth of the ratchet to rotate the latter, an arm pivoted to adapt it to rock to swing the arm carrying the movable roll to carry it away from the opposite roll, and adjustable means on said arm engaged by the pawl-arm at the end of its rocking motion to rock the roll-arm to release the roll from driving contact with the strip.

6. In a coil-winding machine, the combination of a rotating spindle, means for traversing a conductor axially of said spindle, means for feeding a strip of insulating material, a delivery-shelf for receiving the forward end of the strip, means for severing a measured length of the strip at the rear of the delivery-shelf, means for carrying the delivery-shelf forward to deliver the severed length of strip to the winding, reciprocable means for periodically raising the delivery-shelf prior to its forward movement, and automatically-operated means for progressively increasing the range of action of the reciprocable means.

7. In a coil-winding machine, the combination of a winding spindle, means for traversing a conductor axially of the spindle, means for feeding a strip of insulating material, a shelf for receiving the forward end of the strip, means for gripping the end of the strip to the shelf, means for severing a predetermined length of the strip at the rear of the delivery-shelf, a rockable lever, means for pivotally mounting the shelf on said lever, means for rocking the shelf forward on its pivot to deliver the measured length of strip to the coil being wound on the spindle, a reciprocating element for raising the lever to which the shelf is pivoted, a cam connected with said lever and engageable by the reciprocable member, and means to cause the reciprocable member to advance along the cam during the progress of the winding to rock the lever to raise the delivery-

- shelf to a progressively increasing extent as the coil increases in diameter.
8. In a coil-winding machine, the combination of a winding spindle, means for traversing a conductor axially of the spindle, a lever, an arm pivoted to said lever, a delivery-shelf carried by the arm to adapt it to rock toward and away from the winding spindle, means for feeding a strip of material to advance its forward end onto the shelf, means for severing a predetermined length of the strip at the rear of the shelf, a reciprocable member, means for reciprocating said member, a cam-face on the lever carrying the delivery-shelf adapted to be engaged by the reciprocable member, and a cam for displacing the reciprocable member to cause it to advance along the cam-face to progressively increase the extent of lift of the lever and the elevation of the shelf carried thereby.
9. In a coil-winding machine, the combination of a winding spindle, means for traversing a conductor axially of the spindle, means for feeding a strip of insulating material, a delivery-shelf adapted to receive the forward end of the fed strip, means for severing a predetermined length of the strip at the rear of the delivery-shelf, a rockable lever, an arm pivotally mounted on said lever and carrying the delivery-shelf, a rod connected to the arm to rock the latter to move the delivery-shelf toward the winding spindle, a cam, a lever actuated from said cam, and a dog carried by said last-named lever slideable on the rod and adapted to dog thereagainst when the lever is moved in one direction to shift the rod to rock the arm carrying the delivery-shelf.
10. In a coil-winding machine, the combination of a winding spindle, means for traversing a conductor axially of the spindle, means for feeding a strip of insulating material, a delivery-shelf adapted to receive the forward end of the fed strip, means for severing a predetermined length of the strip at the rear of the delivery-shelf, a pivoted arm rockably supporting the delivery-shelf, means for bodily raising said arm after the severance of the strip, a rod connected to rock the arm to carry the delivery-shelf toward the coil being wound, a dog adapted to be rocked to frictionally engage the rod to move the latter, a lever for rocking the dog to engage it with the rod and thereafter move the latter, and means for automatically releasing the dog from the rod.
11. In a coil-winding machine, the combination of a winding spindle, means for traversing a conductor axially of the spindle, means for feeding a strip of insulating material, a delivery-shelf adapted to receive the forward end of the fed strip, means for severing a predetermined length of the strip at the rear of the delivery-shelf, means for moving the delivery-shelf toward the winding spindle to transfer the severed length of strip to the coil, a reciprocable member for elevating the delivery-shelf before its movement toward the spindle, and means for progressively increasing the extent of elevation of the delivery-shelf as the coil increases in diameter.
12. In a coil-winding machine, the combination of a winding spindle, means for traversing a conductor axially of the spindle, means for feeding a strip of insulating material, a delivery-shelf adapted to receive the forward end of the strip, means for gripping the strip on the delivery-shelf, a reciprocable measuring bar movable across the path of the strip to draw out a loop of predetermined length, means for severing the measured length from the strip, means

operated directly by the measuring bar during its return movement to release the gripping means on the delivery-shelf, and means for moving the delivery-shelf toward the winding spindle to apply the severed length of strip to the coil.

13. In a coil-winding machine, the combination of means for winding a conductor, means for feeding a strip of insulating material, delivery means for holding the forward end of the fed strip, means for gripping the strip to the delivery means to prevent its withdrawal therefrom while permitting it to be fed forwardly with respect thereto, said delivery means being movable forwardly and rearwardly with respect to the feeding means, means for drawing out a loop in the strip to measure a predetermined length thereof at the rear of the delivery means, means for severing the measured length, means for moving the delivery means forwardly of the feeding means toward the coil at intervals of the winding to cause the leading end of the strip to be gripped by the winding conductor to draw it into the coil, and means for raising the delivery means with respect to the feeding means during its forward movement whereby it will act to deliver the severed lengths of material adjacent the periphery of the coil.

14. In a coil-winding machine, the combination of means for winding a conductor, means for feeding a strip of insulating material, a delivery-shelf for receiving the forward end of the fed strip, means for clamping the end of the strip to the shelf to prevent it from being withdrawn rearwardly therefrom while permitting it to be drawn forwardly from the shelf, means for measuring a predetermined length of the strip between the delivery-shelf and the feeding means, means for severing the measured length from the strip, means for moving the delivery-shelf toward the coil at intervals of the winding to cause the forward end of the strip to be seized under the conductor being wound to draw it into the coil, means for raising the delivery-shelf with respect to the feeding means during its movement toward the coil, and means acting on the raising means to progressively increase the height to which the shelf is raised during the winding operation in accordance with the increasing diameter of the coil.

15. In a coil-winding machine, the combination of means for winding a conductor, means for feeding a strip of insulating material, a delivery-shelf for receiving the forward end of the fed strip, means for clamping the forward end of the strip to the delivery-shelf to prevent it from being withdrawn rearwardly therefrom while permitting it to feed forwardly with respect thereto, means for severing a measured length of the strip at the rear of the delivery-shelf, means for moving the delivery-shelf forwardly and upwardly toward the coil being wound to adapt it to deliver the severed length of strip thereto, and means for progressively increasing the upward movement at each forward movement of the shelf toward the coil.

16. In a coil-winding machine, the combination of means for winding a conductor, and means for feeding a strip of insulating material between the layers of the wound conductor comprising: a shelf over which the strip is fed, means on the shelf for feeding the strip, a delivery-shelf pivotally mounted for movement from the feeding shelf to the coil being wound, means on the delivery-shelf for gripping the strip of insulating material, means for severing predetermined

lengths of the strip, means for moving the delivery-shelf about its pivot to carry the length of strip from the shelf over which it is fed into engagement with the coil being wound, and means for raising and lowering the pivotal mounting of the delivery-shelf during its forward and rearward movement.

17. In a coil-winding machine, the combination of means for winding a conductor, and means for feeding a strip of insulating material between the layers of the wound conductor comprising: a shelf over which the strip is fed, means on the shelf for feeding the strip, a delivery-shelf pivotally mounted for movement from the feeding shelf to the coil being wound, means on the

delivery shelf for gripping the strip of insulating material, means for severing predetermined lengths of the strip, means for moving the delivery-shelf about its pivot to carry the length of strip away from the shelf over which it is fed into engagement with the coil being wound, and means for raising and lowering the pivotal mounting of the delivery-shelf during its forward and rearward movement, said means progressively actuated during the winding of the coil to increase the height to which the shelf is raised in accordance with the increase in the diameter of the coil. 5 10
